UNITED STATES PATENT OFFICE.

JESSE T. FIESE, OF FRESNO, CALIFORNIA, ASSIGNOR TO LISENBY MANUFACTURING COMPANY, OF FRESNO, CALIFORNIA, A CORPORATION.

ADJUSTABLE BAIL.

1,413,842.

Specification of Letters Patent. Patented Apr. 25, 1922.

Application filed June 25, 1921. Serial No. 480,322.

To all whom it may concern:

Be it known that I, JESSE T. FIESE, a citizen of the United States, residing at Fresno, county of Fresno, State of California, have 5 invented certain new and useful Improvements in Adjustable Bails; and I do declare the following to be a full, clear, and exact description of the same, reference being had to the accompanying drawings, 10 and to the characters of reference marked thereon, which form a part of this application.

This invention relates to improvements in printing presses, and particularly to a paper 15 feed mechanism thereof, such as is shown generally in the type of printing press in United States Patent No. 1,016,756, dated Feb. 6th, 1912, and United States Patent No. 1,041,314, dated Oct. 15th, 1912.

20 The principal object of my invention is to provide for adjustment of the bail feed-roll so that the paper will be gripped and fed over the lower feed plate and into the plane of the printing cylinder with equal pressure 25 on both ends, and without disturbing either the driving arrangement of the roll, or the fixed spacing of the same relative to the bail-post roller.

20 A further object of the invention is to produce a simple and inexpensive device and yet one which will be exceedingly effective for the purposes which it is designed.

These objects I accomplish by means of such structure and relative arrangement of 35 parts as will fully appear by a perusal of the following specification and claims.

In the drawings similar characters of reference indicate corresponding parts in the several views.

40 Fig. 1 is a top plan view of the complete paper-feed mechanism, the adjustable bail structure being emphasized.

Fig. 2 is an end view of the same, the nearest dolly-box being removed.

45 Fig. 3 is a detached rear view of the assembled bail and feed-roll structure.

Fig. 4 is a perspective view of the bail itself.

50 Referring now more particularly to the characters of reference on the drawings, the numeral 1 denotes the side frames of the

press, on which are fixed the dolly-boxes 2, between and in which is journaled the printing cylinder 3, carrying a driving gear 4 on one end, meshing with a rack 5 on the moving bed of the press.

To the rear of the cylinder 3, and on the side thereof opposite the gear 4, is the bail post 6, pivotally mounted to the adjacent dolly box 2 by means of a pin or bearing 60 member 7, and carrying on its opposite end the bail-post feeler-roller 8.

Positioned between the post 6 and the opposite box 2 is the bail 9, comprising a rigid horizontal bar 10 having a narrow 65 vertical arm 11 on one end provided with a bearing orifice 12 to receive the pivotal post-pin 7, and having on the other end an arm 13 extending the full width of the bar 10 provided with a pair of bearing orifices 14 and 15, the former being in transverse and horizontal alinement with the orifice 12, and adapted to receive a bearing pin 16 therethrough, which also passes through the adjacent box 2. 75

On the bearing 16 is mounted an idler pinion 17 interposed between the gear 4 and a pinion 18 on the adjacent end of the bail feed-roll 19, which is journaled at that end in the orifice 15 of the bail-arm, and at the 80 other end in a collar 20 itself turnably mounted in the post 6.

Projecting through the bar 10 and threaded into the collar 20 is an adjustment screw 21, having lock-nuts 22 thereon under said 85 bar.

From the foregoing description it will be noted that the bearing 7, block 20 and roller 8, being all journaled in the bail-post, the distance between their axes are fixed. 90 The bail 9 itself however, is movable relative to the bail post and dolly boxes about the bearings 7 and 16 as axes, and as the bail feed-roll 19 is fixed at one end in the said post, and at the other end in the bail, it is 95 evident that with the swivel movement of said bail about its axes, the horizontal alinement of the feed roll will be altered. Such movement is controlled and governed by the screw 21, so that the said roll may be 100 set exactly parallel to the lower feed roll 23, which is securely fixed to the boxes 2.

The bearing members of the feed roll are allowed sufficient freedom of play in the bail post and bail arm to permit of the slight movement of the roll necessary.

5 From the foregoing description it will be readily seen that I have produced such a device as substantially fulfills the objects of the invention as set forth herein.

While this specification sets forth in detail 10 the present and preferred construction of the device, still in practice such deviations from such detail may be resorted to as do not form a departure from the spirit of the invention, as defined by the appended 15 claims.

Having thus described my invention, what I claim as new and useful and desire to secure by Letters Patent, is:—

1. An adjustable bail structure comprising 20 a bail post, a bail pivoted to the post, a feed roll journaled in the post and in the opposite end of the bail, and means between the bail and roll at the end thereof adjacent

the bail post for altering the horizontal level of the feed roll at the other end.

2. An adjustable bail structure comprising a bail post, a bail pivoted to the post, a feed roll journaled in the post and in the opposite end of the bail, a block turnably mounted in the bail post and in which the adjacent 30 end of the feed roll is journaled, and a headed adjustment screw passing through the bail and threaded into the block.

3. An adjustable bail structure for printing presses comprising a bail post journaled 35 in a fixed member of the press, a bail extending transverse of the press and journaled on the press in common with the post at one end and on the press alone at the other end, a feed-roll member journaled in the post and 40 in the opposite end of the bail, and means for moving the bail about its pivotal connections with the press, whereby the horizontal level of the feed-roll will be altered.

In testimony whereof I affix my signature, 45
JESSE T. FIESE.
